J. M. CUMMINGS AND M. L. CUMMINGS, OF PHILADELPHIA, PENNSYLVANIA.

Letters Patent No. 70,173, dated October 29, 1867; antedated October 15, 1867.

IMPROVED SHUTTER-BOWING BOLT.

The Schedule referred to in these Letters Patent and making part of the same.

TO ALL WHOM IT MAY CONCERN:

Be it known that we, J. M. CUMMINGS and M. L. CUMMINGS, of the city of Philadelphia, in the State of Pennsylvania, have invented a new and useful Improvement in the Shutter-Bowing Bolt; and we do hereby declare that the following is a full, clear, and exact description of the construction and operation of the same, reference being had to the accompanying drawings, making a part of this specification, in which—

Figure 1 is a plane view of the front side of the bolt as it appears when the shutters (not shown) are closed and fastened thereby.

Figure 2 a longitudinal central section of fig. 1, and

Figure 3 a like section of the bolt when in one of its bowed conditions—

Like letters of reference indicating the same parts when in the different figures.

The object of our improvement is to produce a fastening-bolt for window-shutters, whereby the latter can, as occasion may require, be held firmly in any suitably bowed condition, without any liability to be opened by any one from the outer side of the building—a matter of very great importance, and a security against thieves, especially in city residences.

Our invention consists substantially, as hereinafter described and specified, in making the slide or bolt proper to have a T end jointed thereto, which can be operated with facility, in combination with the groove and a stop in the left-hand case of the bolt, so as to allow the shutters to be either bolted when closed, or securely bowed, as occasion may require. And our invention also consists substantially, as hereinafter described and specified, in making the thumb-and-finger piece of the slide or bolt proper adjustable in relation to the latter and to a slot in the right-hand case of the bolt, so as to afford the means for operating the said slide or bolt proper with facility, either in fastening or bowing the shutters.

Referring to the drawings, A is the left-hand case of the bolt, B the right-hand case, C the slide or bolt proper, c' the T end of the said slide, and c'' the thumb-and-finger piece of the same.

The part A of the case consists of a flat plate, a', having two cap-pieces a'' a'' attached or cast on, so as to leave an open space between their upper inner sides and the plate a' for the slide C, and also a clear, open space a''' from end to end, between the two said caps a'', for the stem of the T piece c' to move in when raised up, as shown in figs. 1 and 2.

The part B of the case consists of a flat plate, b¹, and a fixed cap-piece, b², between which the slide C moves longitudinally. The cap b² has two longitudinal slots b³ b⁴, the one, b⁴, for allowing the T piece c' to be turned to the right into it after the slide has been fully drawn back to open the shutters, and the other, b³, for affording the requisite space for the passage of the thumb-and-finger piece c'' in operating the slide C. There is also a through-hole and slot, b⁵, in the plate of the case B, for the reception of the inner end of the piece c'' when the bolt is to be secured in a bowed condition, as will hereinafter be described.

The T piece c' of the slide C is jointed to the end of the latter, and the two are made to be easily moved in the direction of their lengths, under the caps of the cases A and B, by means of the piece c'', but the cross-piece of the T is longer than the width of the slide C, so that when the piece c' is turned in upon the plate a', the cross on c' catches against two stops (see dotted lines 2 2, fig. 1) in the right-hand end of the case A, and thus prevents the slide C from being further withdrawn, but if the piece c' be first turned outward, as shown in figs. 1 and 2, the slide C can then be readily withdrawn entirely from the case A, so as to allow the shutters to be fully or freely opened.

The thumb-and-finger piece c'' has a chamfered circular foot, c''', connected by a circular stem which secures it so that it may be turned around freely in a corresponding hole in the slide C, and also so that it can be pushed inward sufficiently to pass its foot c''' through the round hole b⁵ in the case B, so as to allow the stem to slide along to the end of the slot of the said hole, b⁵, as indicated in fig. 3, and thus prevent the slide C from being moved any further to the left. A small pawl or drop-pin, d, (see fig. 1,) drops its pointed end behind the end of the slide when "shot," and keeps it in place, or locked. The slide C is also notched in two or three places in its upper edge, for the pawl d to catch in, so that various degrees of bowing of the shutters may be securely effected.

In the operation of this bolt, it will be readily seen that when the T piece c' is turned outward, as shown

in figs. 1 and 2, the slide C can be either moved into or out of the case A, in fastening close or opening the shutters; that when the said piece (c') is turned down upon the plate a', it will stop the slide C, when drawn along, until its joint reaches a little beyond the outer end of its case A, where it will be arrested by the stops 2 2, and allow the shutters to be bowed, as shown in fig. 3; that by the thumb-and-finger piece c'' the slotted hole b⁵, and the pawl d, the slide C can be stopped in its case B, so as to secure various degrees of opening in bowing the shutters, and also that the shutters cannot be opened beyond the widest-bowed position or degree, from the outer side of the building, because the T piece c' cannot be detached from its case A until after the shutters have been closed.

Having thus fully described our improvement in the shutter-bowing bolt, what we claim as new therein of our invention, and desire to secure by Letters Patent, is confined to the following, viz:

1. We claim a shutter-bolt having jointed to the end of its slide C a T piece, c', so as to operate in combination with the case A, substantially as and for the purpose described.

2. We also claim in combination with the slide C, having a jointed end, and operating in the case A, substantially as described, the adjustable thumb-and-finger piece c'', and the slotted hole b⁵ in the plate B, substantially as and for the purpose set forth and described.

J. M. CUMMINGS,
M. L. CUMMINGS.
